SLIDER FOR SLIDE FASTENERS

Donald E. Breithaupt, 1216 Camino Vega,
Farmington, N. Mex.

Filed Jan. 29, 1960, Ser. No. 5,456
5 Claims. (Cl. 24—205.14)

This invention relates to the art of fastening devices and, more specifically, the instant invention pertains to the general field of slide fastening devices.

It is common knowledge that the conventional slider for slide fastening devices is so constructed that the outer face thereof is provided with ears, tabs, or other similar bearing projections which extend outwardly from the aforementioned face and between which is supported for pivotal movement a manually manipulative pull tongue.

The heretofore known prior art sliders are possessed of a number of distinct disadvantages among which is the fact that the projecting ears taken together with the overlying pull tongue increase, undesirably, the overall thickness of the slider, *per se*, causing an outward bulge of the material overlying the slider. Aside and apart from unsightly occurrence caused by the bulged-out fabric overlying the slider, the conventional slide fastening devices are also subject to criticism in that the thickness of such devices interferes, materially, with the pressing of the garment or article upon which the slide fastener is affixed. This, in turn, gives rise to the rapid wear of the fabric or material overlying the slide fastener at the particular location of the slider.

Thus, one of the primary objects of the instant invention is to provide an improved slide or slider for a slide fastening device in which the pull tongue, when not in use, is maintained or confined within the slider body. That is to say, the plane of the outer side of the pull tongue will not project beyond the plane of the outer wall of the slider body.

A further primary object of this invention is to provide a slide fastening device incorporating in the pull tongue thereof unique means for locking the slider device against movement relative to the stringer elements when the pull tongue is moved to its locking position.

Another object of this invention is to provide, in the slider for a slide fastening device, a pull tongue which is pivotally connected to the slider body adjacent one end thereof and, more particularly, when the slide fastening device is incorporated in men's and women's clothing, the pull tongue will be pivotally connected to the slider body adjacent the upper end thereof.

A still further object of this invention is to provide a slide for a slide fastening device which is subject to inexpensive mass production, non-complex in construction and assembly and which is durable in use.

Other and further objects and advantages of the instant invention will become more manifest from a consideration of the following specification when read in conjunction with the annexed drawing, in which:

FIGURE 1 is a front elevational view of a slider constructed in accordance with the present invention, the stringer tapes therefor being illustrated fragmentarily;

FIGURE 2 is a longitudinal cross-sectional view of the slider shown in FIGURE 1, FIGURE 2 illustrating the pull tongue in full and dotted lines indicative of its inoperative and operative positions, respectively, FIGURE 2 being taken on the vertical plane of line 2—2 of FIGURE 1, looking in the direction of the arrows;

FIGURE 3 is a bottom plan view of the slider, partly in cross-section, FIGURE 3 being taken on the horizontal plane of line 3—3 of FIGURE 1, looking in the direction of the arrows;

FIGURE 4 is a perspective view of the slider *per se*,

2

with the pull tongue being shown in its inoperative position;

FIGURE 5 is a perspective view of the slider, *per se*, illustrating the pull tongue in its operative position; and,

FIGURE 6 is a perspective view of a second embodiment of this invention.

Referring now more specifically to the drawings, reference numeral 10 designates, in general, a slide fastener constructed in accordance with the teachings of this invention. The slide fastener includes a pair of stringer tapes 12 having confronting edges, and to the outer longitudinally extending marginal edges of which are connected the usual fastener elements or teeth 14. The elements 14 are mounted on the tapes 12 with the elements extending in alternating relation partially across the space intervening between the confronting edge portions. The edge portions here designated at 16, carrying the fastener elements 14, are extended within the outwardly opening sides of the slider, in the usual manner.

The slider 18, to which the instant invention is addressed, comprises outer and inner walls 20, 22, respectively, disposed in parallel planes (see FIGURE 2). The outer and inner walls 20, 22, respectively, at one end portion of the slider 18, shown as the lower end portion in FIGURES 1 to 5, inclusive, are formed with parallel side edges, with the walls remaining of constant width for a part of the length of the slider body, the walls 20, 22 thereafter progressively increasing in width in a direction toward the opposite end of the body which constitutes the upper end of the slider as illustrated in the several figures of the drawing.

This, of course, is a generally conventional configuration of a slider body, it being understood that the tapes are interlocked where they extend out of the narrower end of the body, and are unlocked, in diverging relation, when they extend out of the wider end of the body.

At opposite sides of the body or slide fastener 10, there are provided outwardly facing guide channels 24 for the respective edge portions 16, the channels opening on opposite sides of the body and also opening throughout their length upon the adjacent sides of the body. The walls 20, 22 define side walls for the channels. Inner walls or webs for the channels are defined by a V-shaped guide structure provided in the wider end of the body between the walls 20, 22, said structure comprising divergent walls 23, which walls converge at a location medially between opposite ends of the body, and diverge from this location toward the wider end of the body as is shown to particular advantage in FIGURE 1. The walls 23 extend in laterally inwardly spaced relation relative to the divergent portions of the sides of the body, so as to cause the channels 24 to diverge to impart a corresponding divergence to the stringer tapes where they extend out of the wider end of the slider body. The channels 24, between the point of convergence of the walls 23 and the narrower extremity of the body, are in full communication with each other, since it is in this portion of the length of the body that the fastener elements 14 of the respective edge portions 16 are interlocked (see FIGURE 1).

An end wall 26, at the wider end of the body, terminates at its opposite ends at the divergent extremities of the walls 20, 22.

At the wider end of the body, the channels 24 are of maximum width, and inwardly a short distance from this extremity of the channels, the channels are narrowed where they open upon the sides of the body, through the provision of confronting longitudinal flanges formed upon opposite sides of the side walls 20, 22. These flanges are designated at 28, 30, respectively.

Intermediate the length of the body, the wall 20 is

formed, immediately between opposite sides thereof with a shallow depression 32 which open outwardly and downwardly of the side wall 20. As is clearly seen in FIGURES 2 and 5, the depression extends upwardly and terminates adjacent the top wall 26.

The side wall 20 is also stamped or otherwise formed with a transversely extending opening 34 (see FIGURE 2) across which extends a support rod 36.

Reference numeral 38 denotes a substantially rectangular pull tongue having a hinge barrel 40 at its upper end integrally formed therewith. As is seen in FIGURES 2 and 5, the hinge barrel 40 is rotatably mounted upon the support rod 36.

The pull tongue 38 extends downwardly from the support rod 36 for a distance below the lower ends of the side walls 20, 22, and spaced inwardly from the lower end of the pull tongue 38 and adjacent the lower end of the side wall 20, is a transversely extending substantially rectangular slide fastener lock member 42.

Referring now to FIGURES 1 to 3, inclusive, the lock element 42 is recessed at 44 at one end thereof providing a depending shoulder 46 at its other end.

In operation, and assuming that stringer tapes 12 are engaged within the slider 18 in the conventional manner, as illustrated in FIGURES 1 and 2, and assuming further that it is now desired to lock the slider at a given point thereon, the operator moves the pull tongue 38 from its open position shown in FIGURE 5 to its closed position shown in FIGURE 4, thereby causing the lock member 42 to extend across the fastener elements 14. In this construction, one of the fastener elements 14 will be overlapped by the cutout portion 44 of the lock member 42, and the shoulder 46 will enter between a pair of fastener elements on the other of the tapes to securely hold the tapes against relative movement with respect to each other.

It should be noted at this point that the pull tongue 38, when in its inoperative position, is substantially flush with the side wall 20, that is, the outer plane of the pull tongue 38 is substantially coincident with the outer plane of the side wall 20.

Reference is now made to FIGURE 6 of the drawing in which a second embodiment of this invention is illustrated. To avoid repetition, elements of this second embodiment of the invention finding counterparts in the first embodiment have been assigned identical reference numerals to which a prime mark has been added to clearly differentiate between the two inventions.

Essentially, the two inventions are or may be distinguished one from the other in that the shell depression 32' includes a bight 50 which extends longitudinally and centrally of the wall 20 throughout its entire length. The bight 50, adjacent the wider end of the wall 20 is formed with a slot 51 and the top wall 26' is formed with a slot 52 which gives rise to a transversely extending substantially rectangular bar 54 around which extends the hinge barrel 40' of the pull tongue 38'. In all other respects, the structure and function of the slide 18' is identical to the slide 18 described above.

It should now be self evident that a slider 18, 18' for a slide fastener constructed in the manner described above, eliminates all unsightly bulges in fabric material lying thereabove and, at the same time, materially decreases wear on the garment or other article to which the slide fastener is attached.

Having described and illustrated one embodiment of this invention in detail, it will be understood that the same is offered merely by way of example and that this invention is to be limited only by the scope of the appended claims.

What is claimed is:

1. A slide for a slide fastener comprising a body having inner and outer walls defining between them longitudinal guide channels extending along opposite sides thereof, said channels each being adapted to receive a stringer tape therethrough, said outer wall having a depression

formed therein opening outwardly therefrom and outwardly of one end thereof, said outer wall having an opening extending transversely therethrough adjacent the other end thereof, a support bar disposed in the plane of said outer wall and traversing said opening, a pull tongue having an end thereof pivotally connected on said support bar and being movable into and out of said depression, said pull tongue when disposed within said depression having an opposed end thereof projecting beyond said one end of said outer wall, a lock member extending across said projecting end of said pull tongue, said lock member when said pull tongue is pivoted into said depression lockably engaging between adjacent fastener elements of one of said stringer tapes.

2. A slide for a slide fastener comprising a body having inner and outer walls defining between them longitudinal guide channels extending along opposite sides thereof, said channels each being adapted to receive a stringer tape therethrough, said outer wall having a depression formed therein opening outwardly therefrom and outwardly of one end thereof, said outer wall having an opening extending transversely therethrough adjacent the other end thereof, a support bar disposed in the plane of said outer wall and traversing said opening, a pull tongue having a hinge barrel at one end thereof pivotally supported on said support bar, said pull tongue being movable into and out of said depression, said pull tongue when disposed within said depression having an opposed end thereof projecting beyond said one end of said outer wall, a lock member extending transversely across said projecting end of said pull tongue, said lock member when said pull tongue is pivoted into said depression being disposed substantially adjacent said one end of said outer wall and lockably engaging between adjacent fastener elements of one of said stringer tapes.

3. A slide for a slide fastener comprising a body having inner and outer walls defining between them longitudinal guide channels extending along opposite sides thereof, said channels each being adapted to receive a stringer tape therethrough, said outer wall having an elongated substantially rectangular depression formed centrally therein and opening outwardly therefrom and outwardly of one end thereof, said outer wall having an opening extending transversely therethrough adjacent the other end thereof, a support bar disposed in the plane of said outer wall and traversing said opening, a pull tongue having an end thereof provided with a hinge barrel surrounding said support bar whereby said pull tongue may be pivoted into said depression, the outer planar surface of said outer wall and the outer planar surface of said pull tongue being coincident, said pull tongue when disposed within said housing having an opposed end thereof projecting beyond said one end of said outer wall, a lock member projecting across said last named end of said pull tongue, said lock member having a substantially rectangular configuration and having a cutout portion projecting inwardly from one end thereof to form an outwardly projecting shoulder at the other end thereof, said shoulder when said pull tongue is pivoted into said depression lockably engaging between adjacent fastener elements of one of said stringer tapes and said cutout portion of said lock member spanning across one locking element of the other of said tapes.

4. A slide for a slide fastener comprising a body having inner and outer walls defining between them longitudinal guide channels extending along opposite sides thereof, said channels each being adapted to receive a stringer tape therethrough, said outer wall having a depression formed therein and extending longitudinally therethrough from end to end thereof, said depression forming a bight 70 portion in said outer wall, said bight having a slot formed therein adjacent one end thereof and extending transversely thereacross, a wall extending across and connecting said one end of said outer wall with the adjacent end of said inner wall, said last named wall having a slot formed therein extending parallel to said first slot

thereby giving rise to a transversely extending support bar, a pull tongue having an end thereof pivotally connected on said support bar and being movable into and out of said depression, said pull tongue when disposed within said depression having an opposed end thereof projecting beyond said one end of said outer wall, a lock member extending transversely across said projecting end of said pull tongue, said lock member when said pull tongue is pivoted into said depression lockably engaging between adjacent fastener elements of one of said stringer tapes.

5. A slide for a slide fastener comprising a body having inner and outer walls defining between them longitudinal guide channels extending along opposite sides thereof, said channels each being adapted to receive a stringer tape therethrough, said outer wall having a depression formed therein and extending longitudinally therethrough from end to end, said outer wall including a bight portion at the inner end of said depression, said bight portion having a slot formed therein adjacent an end thereof to form a support bar, said support bar traversing said depression, a pull tongue having a hinge barrel at one end thereof pivotally supported on said support bar, said

10 pull tongue being movable into and out of said depression, said pull tongue when disposed within said depression having an opposed end thereof projecting beyond said one end of said outer wall, a lock member extending transversely across said projecting end of said pull tongue, said lock member when said pull tongue is pivoted into said depression being disposed substantially adjacent said one end of said outer wall and lockably engaging between adjacent fastener elements of one of said stringer tapes, and said pull tongue, when pivoted into said depression, having its outer planer surface coincident with the outer planar surface of said outer wall.
